Primary Examiner—Brian N. Vinson
Attorney, Agent, or Firm—Staas & Halsey**[57] CLAIM**

The ornamental design for a "select function" icon for a display screen, as shown and described.

DESCRIPTION

The single FIGURE is a front elevational view of a "select function" icon for a display screen showing my new design, the broken-line disclosure of a portion of a screen being understood to form no part of the claimed design.

1 Claim, 1 Drawing Sheet
